TIMING DEVICE FOR CAM GRINDING MACHINES

Conrad L. Ott, Waynesboro, Pa., assignor to
Landis Tool Company, Waynesboro, Pa., a corporation of Pennsylvania

Application July 10, 1930, Serial No. 467,045
Renewed April 18, 1932

23 Claims.

(Cl. 51—72)

This invention relates to devices for timing the grinding of each cam in a cam grinding machine and is designed primarily for use in machines of the kind shown in the co-pending application of Amos P. Steiner, Edgar P. Wine, Conrad L. Ott and Harold E. Balsiger, Serial No. 384,068, for Cam grinding machines, filed August 7, 1929, and the object is to provide an improved timing device which will be accurate and highly sensitive.

10 Referring to the accompanying drawings, which are made a part hereof and on which similar reference characters indicate similar parts,

Fig. 1 is a front view of an elevation of a cam grinding machine having my invention incorporated therein and

15 Figure 2 is a view in elevation, partly in section, of the device showing the fluid circuits and the various fluid motors somewhat diagrammatically.

20 In the drawings numeral 10 indicates a bar mounted on the traverse carriage of a grinding machine and 11 indicates a plunger adapted to seat in notches 12 in the bar to hold the traverse carriage in the several operative positions necessary for grinding the several cams on a cam shaft.

25 The plunger 11 is attached to the rear end of a lever 13 which is pivoted on the base of the grinding machine at 14 and has a beveled end 15 adapted to engage a beveled lug 16 on a cam

30 17. The lug 16 is beveled so as to permit the cam 17 to rotate counterclockwise, said rotation causing the left end of a lever 13 to be raised to release the plunger 11 from the notches 12. The cam 17 is mounted on a shaft 18 and is rotated

35 through a series of gears 19, 20 and a worm gear 21 mounted on a shaft 22. The end of the shaft 22 has a clutch 23 keyed thereto which clutch may slide axially on the shaft 22 to bring it into and out of engagement with a clutch 24 on shaft

40 25. The shaft 25 is continuously rotated by means of a sprocket chain 26, said chain being driven by any suitable mechanism on the grinding machine. Numeral 27 indicates the motor which drives the traverse carriage, 28 indicates the

45 motor which moves the wheel base into and out of grinding position, 29 indicates the motor which moves the work supporting cradle toward and from grinding wheel, 30 indicates the reversing valve for the traverse carriage and 31 indicates

50 the pump for supplying motive fluid to the several motors. The motors just mentioned are similar in all respects to those shown in the co-pending application referred to and since no claim is made for novelty in respect to them they will not be

55 further described. 32, 33, 34, 35, 36 and 37 indi-

cate fluid circuits to the several motors; 38 indicates the control valve for the motors. A plunger 39 having valve disks 53 is mounted to slide within the valve 38. The rear end of the lever 13 rests upon the upper end of the plunger 39. From the view as shown it will be apparent that the valve disk 53 controls passage of fluid from the pressure line 32 into the line 40 through which fluid may flow to the line 36 and to each of the motors 28 and 29. Fluid will first flow through 10 the line 40 as it will be noted that the entrance to this line is slightly above the entrance to the line 33 to operate wheel base and cradle before work carriage. The wheel base and the work cradle therefore will move back as soon as the 15 plunger 39 is slightly depressed. When the valve has been further depressed the line 33 will be opened so that the fluid may flow through this line through the valve 30 to the line 34 or 35 depending on the position of the reverse valve 54 20 to move the traverse carriage. Fluid also will flow from the line 40 through a restriction 42 to the line 41 and act against a valve 43 to move this to the left against the tension of a spring 44. The tension of the spring is regulated by a nut 25 45. When the valve 43 has been moved sufficiently far to the left fluid may flow from the line 41 into the chamber 55 where it acts against a piston 46 to move this to the left to move clutch 23 out of engagement with clutch 24 and stop rotation of the cam 17. 52 denotes the work rotating motor and 51 a limit switch which controls the speed of the motor 52 so that at a predetermined point in the grinding of a cam the work rotating motor is slowed down during the polishing of a cam as is more fully described in the co-pending application referred to. At 50 is shown a latch by means of which the lever 13 may be held down so as to allow the traverse carriage to be freely reciprocated. 49 denotes 30 the usual relief valve in the discharge line from the pump.

45 The operation of the invention is as follows: During grinding of a cam the timing cam 17 is driven slowly through the gearing connection described. The speed of this cam is timed so as to permit the work to be completely ground during one revolution of cam 17. When the lug 16 strikes the beveled end 15 of the lever 13, the lever is rocked on its pivot to release the plunger 11 from 50 engagement with a notch on the bar 10. At the same time the valve 39 is depressed and pressure fluid line 32 is put into communication with pressure line 40 and through line 36 the wheel base and work cradle are operated to move them 55

out of position so that the traverse carriage may be moved. As the disk 53 moves down further pressure line 32 is put into communication with line 33 to move the traverse carriage. Pressure fluid would tend also to enter the line 41 to move back the valve 43 and release the clutches 23 and 24. If there were no restriction at 42 the cam 17 would be stopped at the instant that the valve plunger 39 is pressed down. This would stop the cam with the beveled end 15 riding on the top of the lug 16. A restriction at 42 is provided therefor so that the cam 17 may move for a short time after the valve 39 is depressed. The size of the restriction 42 is such that the valve 43 will move back in time to cause the cam 17 to stop rotation at the instant the lug 16 has reached the position shown in the figure. This time may be controlled by the tension lug nut 45. When the traverse carriage reaches the position at which the plunger 11 may enter the next notch it is locked in this position. The plunger 39 is moved to its upward position by means of a spring 56. When the plunger is moved again to lock the carriage in position the valve disk 53 moves up to shut off pressure fluid from line 32 and to connect line 40 with the exhaust line 48. As the valve 43 moves to the right chamber 55 is opened to exhaust port 47, spring 57 then moves piston 46 to the right to bring clutch 23 into engagement with clutch 24.

It will be obvious to those skilled in the art that various changes may be made in my device without departing from the spirit of the invention and therefore I do not limit myself to what is shown in the drawings and described in the specification, but only as indicated in the appended claims.

Having thus fully described my said invention, what I claim as new and desire to secure by Letters Patent, is:

1. In a grinding machine having a grinding wheel and a traversible work carriage, and means for locking the work carriage in work grinding position, means for timing movement of the said carriage comprising a cam, a constantly moving wheel and a clutch for connecting said cam operatively with said constantly moving member, means for moving said carriage, and means for releasing said clutch after said carriage is caused to move, substantially as set forth.

2. In a cam grinding machine, a traverse carriage locking bar, a fluid motor for moving said bar, pressure fluid lines for operating said motor, means for locking the bar in any one of several predetermined positions to which it is moved, means for releasing said locking means, means operated by pressure from said fluid lines for making said releasing means inoperative, said motor being operated slightly in advance of said last named means due to a restriction in the fluid line to said last named means, substantially as set forth.

3. In a cam grinding machine having a notched bar for holding the cam to be ground in any one of several predetermined positions, a fluid motor for moving said bar, a plunger engageable with the bar to lock it in position, a lever for operating said plunger, a pressure fluid line to said motor, a valve controlling fluid to said motor, said valve being operated by said lever, a rotary cam having a lug for engaging said lever to release the plunger from engagement with the said bar, a constantly driven shaft, a clutch operatively connecting said shaft with means for rotating the cam, and means whereby when the said plunger is released from

the said bar the said clutch will be disengaged to stop rotation of the said cam, said means first causing operation of said motor to start movement of said bar before rotation of said cam is stopped, substantially as set forth.

4. In a cam grinding machine having a traverse carriage and operating means for said carriage, means for locking the carriage in grinding position, means for releasing the locking means for said carriage, means for timing the releasing means to determine the time during which a cam is ground, driving means for timing means, and means interrupting said driving means during movement of said carriage, there being a short interval between the interruption of said driving means for the timing means and the movement of the said traverse carriage, substantially as set forth.

5. A timing mechanism for a grinding machine comprising a timing cam, means for driving said cam comprising a constantly driven mechanism a connection between said cam and the said mechanism, means to render said connection operative or inoperative, and means to render said connection operative only during the active grinding operation, substantially as set forth.

6. A timing mechanism for a grinding machine comprising a power driven timing cam, a connection between said cam and the source of power, a control valve operated by said cam for controlling the movements of the machine, and means whereby said control valve operates to render said connection operative or inoperative, substantially as set forth.

7. A timing mechanism for a grinding machine comprising a power driven timing cam, a connection between said cam and the driving means, a control valve operated by said cam for controlling the movements of the machine, means whereby said control valve operates to render said connection operative or inoperative, and means whereby said cam rotates through a predetermined distance after said valve has been shifted, substantially as set forth.

8. A timing mechanism for a grinding machine comprising a power driven timing cam, a connection between said cam and the driving means, a control valve operated by said cam for controlling the movements of the machine, means whereby said control valve operates to render said connection operative or inoperative and a restriction between said valve and said connection to retard the opening of said connection, substantially as set forth.

9. The combination with the locking bar on a carriage, a locking means cooperating with said locking bar, of a timing device in control of said locking means, means for operating said timing device, means for interrupting the operation of the timing device at predetermined intervals, and means controlled by said timing device for causing movement of said carriage while said timing device is inactive.

10. In a grinding machine having a carriage, means for moving it and means for locking it in successive predetermined positions, a timing device in control of said locking means, a fluid motor in control of said timing device and a valve in control of means for moving said carriage, said valve being operated by release of said locking means, said fluid motor being controlled by the said valve, substantially as set forth.

11. In a cam grinding machine having a work carriage, a wheel carriage and a work cradle, hydraulic motors for effecting movement of the car-

riages and work cradle and means for locking the work carriage in grinding position, a cam for controlling releasing of said locking means, means for operating said cam, a fluid motor in control of said means, a restriction in the fluid line to said motor, a fluid motor for operating the wheel carriage, the pressure fluid line to said motor being in communication with the said first-named fluid motor, the said cam means having means engageable locking means for causing withdrawal of the wheel base and the work cradle, the said restriction causing withdrawal of the wheel carriage slightly in advance of indexing of the work carriage, substantially as set forth.

12. In a cam grinding machine having means for operating a work carriage, a work cradle and a wheel base, means for locking the work carriage in successive positions to locate a cam in grinding position, a cam for releasing said locking means, means for operating said cam, a fluid motor in control of said operating means, fluid motors for operating the work carriage and the wheel base, and a restriction in the fluid line to the first named motor, said cam also causing operation of the said wheel base, work cradle and work carriage, the work cradle and wheel base being operated slightly in advance of operation of the work carriage, substantially as set forth.

13. Timing mechanism for a grinding machine comprising a timing cam, driving mechanism for said cam, a releasable connection between said cam and said driving mechanism, means operated by said cam for controlling the movement of the machine, and means whereby said control means operates to render said connection effective or ineffective for intermittently controlling the rotation of said cam, substantially as set forth.

14. Timing mechanism for a grinding machine comprising a power driven timing cam, releasable connection between said cam and the driving means, means operated by said cam for controlling the movement of the machine, means whereby said controlling means operates to render said connection operative or inoperative for intermittently controlling the rotation of said cam, and means whereby said cam rotates through a predetermined distance after said control means has operated, substantially as set forth.

15. A timing mechanism for a grinding machine comprising a power driven timing cam, a connection between said cam and the driving means therefor, control means operated by said cam for controlling movements of the machine, means whereby said control means operates to render said connection operative or inoperative, and means for delaying operation of said control means to delay operation of said work carriage until after said wheel carriage has moved to the limit of its travel in a given direction, substantially as set forth.

16. In a cam grinding machine, a work carriage, a wheel carriage, a fluid motor for moving the wheel carriage toward and from the work, a second fluid motor for traversing the work carriage past the grinding wheel, a bar having a plurality of spaced notches corresponding to the cams on the shaft to be ground and adapted to receive a plunger to lock the carriage in place during the grinding of a cam, means for timing the grinding operation comprising a rotatable timing cam, means operated by said timing cam for withdrawing the locking plunger, a drive connection between operable mechanism on the machine and the said timing cam, a clutch for con-

necting and disconnecting said driving connection and means operating to disconnect said clutch whereby said timing mechanism is inoperative during traverse of said work carriage, substantially as set forth.

17. In a cam grinding machine, a work carriage, a wheel carriage, a fluid motor for moving the wheel carriage toward and from the work, a second fluid motor for traversing the work carriage past the grinding wheel, a bar having a plurality of spaced notches corresponding to the cams on the shaft to be ground and adapted to receive a plunger to lock the carriage in place during the grinding of a cam, means for timing the grinding operation comprising a rotatable timing cam, means operated by said timing cam for releasing the locking plunger, a drive connection between operable mechanism on the machine and the said timing cam, and a clutch for connecting and disconnecting said driving connection, withdrawal of said plunger serving also to disconnect said clutch whereby said timing cam is inoperative during traverse of said work carriage, substantially as set forth.

18. In a cam grinding machine, a wheel base, a work carriage, means for traversing the work carriage, means for locking it in any one of a plurality of predetermined positions, means for releasing the locking means, a timing cam in control of said releasing means, means for operating said timing cam, and means for rendering said timing cam inoperative during the traverse of the said work carriage, substantially as set forth.

19. In a cam grinding machine, a work carriage, a wheel base, a work cradle, means for moving each of said mechanisms to operative and inoperative positions, means for indexing the work carriage to bring successively the various cams into position before the grinding wheel, means for locking the carriage in fixed grinding position, a timing cam for controlling indexing of the work carriage, and means for rendering said timing cam operative only when the work carriage, the wheel base and the work cradle all are in operative grinding position, substantially as set forth.

20. A cam grinding machine having a wheel base, a work carriage and a work cradle, each of which is operated by a separate fluid motor, a single valve in control of each of the fluid motors, a timing cam in control of indexing of the work carriage, said timing cam controlling also operation of the said valve, substantially as set forth.

21. A cam grinding machine having a wheel base, a work carriage and a work cradle, each of which is operated by a separate fluid motor, a single valve in control of each of the fluid motors, a timing cam in control of indexing of the work carriage, said timing cam controlling also operation of the said valve, said valve being so arranged that at the end of grinding a single shaft, fluid to the work carriage is cut off and the work cradle and wheel base are withdrawn to inoperative position, substantially as set forth.

22. In a cam grinding machine, a control valve having fluid connections, therefrom to operate a wheel base, work carriage, and work cradle, a timing cam for operating said valve, means to drive said timing cam, means for locking the work carriage in correct position for grinding a cam, means controlled by the said cam for releasing the locking means, and causing withdrawal of the wheel base and work cradle, and traversing of the work carriage, and means controlled by move-

65

ment of the work carriage to prevent rotation of said timing cam during the traversing movement, substantially as set forth.

23. In a cam grinding machine, a control valve having fluid connections therefrom to operate a wheel base, a work carriage, and work cradle, a timing cam for operating said valve, means to drive said timing cam, means for locking the work carriage in correct position for grinding a cam,

means controlled by said cam for releasing the locking means, and causing withdrawal of the wheel base and work cradle, and traversing of the work carriage, and means acting in timed relation with the movement of the carriage to stop rotation of said timing cam while the wheel base is in inoperative position, substantially as set forth.

CONRAD L. OTT.
